OIL WELL DERRICK

Homer J. Woolslayer, Cecil Jenkins, and William H. Lutgen, Tulsa, Okla., assignors to Lee C. Moore Corporation, Pittsburgh, Pa., a corporation of Pennsylvania

Application September 25, 1948, Serial No. 51,226

8 Claims. (Cl. 189—15)

1

This invention relates to portable oil well derricks, and more particularly to those which include masts that can be divided transversely into long sections for transportation on trucks and the like. When such masts are taken down and loaded upon trucks or are unloaded and assembled, they have required, in addition to the trucks that transport them, the services of other trucks equipped with gin poles and winches.

It is among the objects of this invention to provide portable oil well derrick equipment including a mast which can be transported from one location to another by a single truck and which can be loaded thereon and unloaded without the services of a gin pole truck. Another object is to provide a new method of loading such a mast on a vehicle and unloading it therefrom.

In accordance with this invention an oil well mast has an upper section and a lower section detachably connected together. The upper section may be further subdivided if desired. At least the lower section has an open front. A track extends lengthwise of the outside of the back of the upper section, while bearing members are carried by the upper end of the lower section. Means are provided for pivotally connecting the lower end of the mast to a substructure so that the mast can be swung forward and downward from an upright position to a prone position to permit its upper section to rest on a vehicle that is to transport it to another location. Means, such as a winch on the vehicle, is provided for lifting the front end of the prone lower section after it has been disconnected from the prone upper section to set the bearing members on the track. Movement of the vehicle toward the substructure will then telescope the upper section of the mast into its lower section which is not disconnected from the substructure until the mast sections have been nested on the vehicle. The lower end of the mast preferably is pivotally connected to the rear end of an arm means which is pivoted at its front end on a horizontal axis to the top of the substructure of which it forms a part. When the mast is swung down onto the vehicle, the arm means can swing upward to permit the lower end of the mast to rise so that the mast can lie flat on the vehicle while still attached to the substructure.

The invention is illustrated in the accompanying drawings in which Fig. 1 is a plan view of the substructure; Fig. 2 is a side view thereof with one of the side members broken away; Figs. 3

2

to 6 are line drawings of the side of the derrick showing the mast in several successive positions as it is loaded on a truck; Fig. 7 is a fragmentary side view of the connected ends of the upper 10 and lower sections of the prone mast; Fig. 8 is similar to the preceding view but with the lower section of the mast disconnected from and straddling the upper section; Fig. 9 is a cross section of the mast taken on the line IX—IX of Fig. 8; and Fig. 10 is a cross section of the mast taken on the line X—X of Fig. 6.

Referring to Figs. 1 and 2 of the drawings, the substructure 1 is a strong framework formed from structural steel members suitably connected together, and has two vertical side frames 2 connected by cross members 3 and by a removable horizontal frame 4 at its front end. The substructure is provided with arm means which consists of a pair of horizontal arms 6 connected at their front ends to horizontal pivots 7 in the upper part of the side frames. The upper surfaces of the arms preferably are flush with the upper surface of the rest of the substructure. Mounted on the rear end of each arm is a shoe 8 for pivotally supporting the rear leg 9 of a mast. The front legs 11 of the mast are supported by shoes 12 mounted on the front end of the substructure. Behind the arms the side frames are provided with shoes 13 and 14 for supporting the legs of a gin pole 16 which aids in the raising and lowering of the mast when the front legs of the mast are disconnected from shoes 12. The particular way in which the mast is raised and lowered by a line from the draw-works running over the gin pole and crown block need not be described here because by now it is well known in this art. The mast is formed from upper and lower sections 17 and 18 which are detachably connected together by removable fasteners 19 through their legs, as shown in Fig. 7. At least the lower section has an open front which faces down when the mast is prone, as shown in Figs. 9 and 10, and the front of the mast preferably is wider than its back for a reason that soon will appear. The upper section may be formed from shorter sections detachably connected end to end if desired.

It is a feature of this invention that a track extends lengthwise of the outside of the back of upper section 17 of the mast. The track may be formed from a pair of parallel angle bars 21 secured to the back girts 22 of the mast. Mounted inside the upper or front end of lower section 18 of the prone mast is a pair of bearing members, such as rollers 23 shown in Fig. 7, which are

55

carried by side girts 24. These rollers are spaced apart such a distance that they can roll on the track. The rear ends of the track rails have extensions 26 that are inclined downward and toward the substructure and are provided with upwardly curved ends 27 in which the rollers normally are disposed. When the mast is in its prone position and fasteners 19 are removed, the rollers can be supported by these curved ends of the track. Between the substructure and the side girts 24 that support the rollers the front legs of the mast are provided with perforated lugs 28 to which the ends of a bridle line 29 can be detachably connected after the mast has been let down onto the truck. The line then is passed over sheaves 31 mounted in the lower or rear end of the prone upper section of the mast near its rear legs, and the loop at the front end of the line is connected to another line 32 (Fig. 3) which is attached to a winch 33 mounted on the truck directly behind the cab.

When it is desired to lower the mast from upright operative position its front legs are disconnected from the front shoes 12 on the substructure, the lower sections of the front legs either then being swung back out of the way or being disconnected from the mast. The horizontal frame 4 is removed from the substructure to form a bay for receiving the mast when necessary. The mast then is swung forward and down in a well known manner until its upper section rests prone on the truck. Regardless of the elevation of the truck relative to the substructure, the mast will rest flat on the truck because the pivoted arms 6 permit the lower end of the mast to rise above the substructure the amount necessary to level the mast, as shown in Fig. 3. Yet, the mast remains connected to the substructure through the arms. Fastening members 19 then are removed in order to disconnect the upper and lower sections of the mast, and the bridle line 29 is connected to lugs 28 and to the winch line 32 which then is reeled in to lift the upper or front end of the prone lower section 18 while the truck is being backed a short distance toward the substructure. This causes rollers 23 to roll up the inclined track extensions 26 and onto the main track as shown in Figs. 4 and 8. The bridle line then is disconnected from lugs 28 because the front end of lower section 18 now is supported astraddle of the other section 17 by means of the rollers and track, as shown in Fig. 9. The taper of the mast from front to back permits this straddling without having to lift the front end of the lower section as high as otherwise would be necessary. The truck then is backed again so that the upper section 17 of the mast on the truck will move back through the lower section which is prevented by the arms from moving backward, as shown in Fig. 5. In this way the upper section of the mast is telescoped into the lower section until the two sections are nested with their front legs all resting on the truck as shown in Figs. 6 and 10. The rear legs of the lower section then are disconnected from the substructure arms 6 so that the truck can be driven away with the nested mast sections on it.

In erecting the mast this procedure is just reversed. That is, the truck with the nested mast sections on it is backed up to the substructure and arms 6 are raised so that their shoes 8 can be connected to the rear legs 9 of the lower section of the mast, as shown in Fig. 6. The

truck then is driven forward to move the upper section 17 of the mast nearly out of the lower section 18. During this operation rollers 23 roll on the track 21. When the rear end of the main track reaches the rollers, the bridle line 29 is attached to lugs 28 and to winch line 32 and then the rollers are allowed to roll down track extension 26 until they rest in the curved lower ends 27 of the rails. This leaves the two sections of the mast in position to be connected together by fastening members 19 (Figs. 3 and 7) to form a unitary mast that can be swung up into upright position in the usual manner. When the mast is upright the arms 6 are in their lower horizontal position in the top of the substructure, and the front legs of the mast are connected to the front shoes 12.

It will be seen that this invention enables a mast to be mounted in sections on a single truck, or to be unloaded therefrom, without the use of a gin pole truck or any winch additional to the one on the truck carrying the mast.

According to the provisions of the patent statutes, we have explained the principle of our invention and have illustrated and described what we now consider to represent its best embodiment. However, we desire to have it understood that, within the scope of the appended claims, the invention may be practiced otherwise than as specifically illustrated and described.

We claim:

1. An oil well derrick comprising a substructure, a mast having an upper section and an open front lower section detachably connected together, said sections being of such shape that the upper section is capable of being telescoped into the lower section when they are disconnected from each other, a track extending lengthwise of the outside of the back of said upper section, bearing members carried by the upper end of said lower section, means pivotally connecting the lower end of the mast to the substructure so that the mast can be swung forward and down from an upright position to a prone position thus permitting its upper section to rest on a vehicle, and means lifting the upper end of the prone lower section after it has been disconnected from the prone upper section and seating said bearing members on the track, whereby movement of the vehicle toward the substructure will telescope the upper section of the mast into its lower section, after which the lower end of the mast can be disconnected from the substructure to permit the nested mast sections to be carried away by the vehicle.

2. An oil well derrick comprising a substructure, an upwardly tapered upright mast mounted thereon having an upper section and an open front lower section detachably connected together, a track extending lengthwise of the outside of the back of said upper section, rollers mounted in the upper end of said lower section, means pivotally connecting the lower end of the mast to the substructure so that the mast can be swung forward and down to a prone position thus permitting its upper section to rest on a vehicle, and means lifting the upper end of the prone lower section after it has been disconnected from the prone upper section and seating said rollers on the track, whereby movement of the vehicle toward the substructure will telescope the upper section of the mast into its lower section, after which the lower end of the mast can be disconnected from the substructure to permit the

nested mast sections to be carried away by the vehicle.

3. An oil well derrick comprising a substructure, an upright mast having an upper section and an open front lower section detachably connected together and having front and rear legs detachably mounted on the substructure, the mast having forwardly diverging sides, a track extending lengthwise of the outside of the back of said upper section, rollers mounted on opposite sides of the mast inside the upper end of said lower section about midway between said legs, means pivotally connecting said rear legs to the substructure so that the mast can be swung forward and down to a prone position thus permitting its upper section to rest on a vehicle, and means lifting the upper end of the prone lower section after it has been disconnected from the prone upper section and seating said rollers on the track, whereby movement of the vehicle toward the substructure will telescope the upper section of the mast in its lower section, after which the rear legs of the mast can be disconnected from the substructure to permit the nested mast sections to be carried away by the vehicle.

4. An oil well derrick comprising a substructure, an upright mast mounted thereon having an upper section and an open front lower section detachably connected together, said sections being of such shape that the upper section is capable of being telescoped into the lower section when they are disconnected from each other, a main track extending lengthwise of the outside of the back of said upper section, a track extension extending from the lower end of said main track forward into the mast, rollers mounted in the upper end of said lower section adjacent said track extension, means pivotally connecting the lower end of the mast to the substructure so that the mast can be swung forward and down to a prone position thus permitting its upper section to rest on a vehicle, and means lifting the upper end of the prone lower section after it has been disconnected from the prone upper section and rolling said rollers up said track extension to the main track, whereby movement of the vehicle toward the substructure will telescope the upper section of the mast into its lower section, after which the lower end of the mast can be disconnected from the substructure to permit the nested mast sections to be carried away by the vehicle.

5. An oil well derrick comprising a substructure, an upright mast mounted thereon having an upper section and an open front lower section detachably connected together, said sections being of such shape that the upper section is capable of being telescoped into the lower section when they are disconnected from each other, a main track extending lengthwise of the outside of the back of said upper section, a track extension inclined from the lower end of said main track forward and downward into the upper end of said lower section, rollers supported by the opposite sides of said lower section in engagement with said track extension, means pivotally connecting the lower end of the mast to the substructure so that the mast can be swung forward and down to a prone position thus permitting its upper section to rest on a vehicle, and means lifting the upper end of the prone lower section after it has been disconnected from the prone upper section and rolling said rollers up said track extension to the main track, whereby

movement of the vehicle toward the substructure will telescope the upper section of the mast into its lower section, after which the lower end of the mast can be disconnected from the substructure to permit the nested mast sections to be carried away by the vehicle.

6. An oil well derrick comprising a substructure, an upright mast mounted thereon having an upper section and an open front lower section detachably connected together, said sections being of such shape that the upper section is capable of being telescoped into the lower section when they are disconnected from each other, a main track extending lengthwise of the outside of the back of said upper section, a track extension extending from the lower end of said main track forward into the mast and having a downturned front end, rollers mounted in the upper end of said lower section behind said downturned track end in engagement with it, means pivotally connecting the lower end of the mast to the substructure so that the mast can be swung forward and down to a prone position thus permitting its upper section to rest on a vehicle, said rollers being supported by said downturned track end when the prone lower section of the mast is disconnected from the prone upper section, and means lifting the upper end of the disconnected lower section and rolling said rollers up said track extension to the main track, whereby movement of the vehicle toward the substructure will telescope the upper section of the mast into its lower section, after which the lower end of the mast can be disconnected from the substructure to permit the nested mast sections to be carried away by the vehicle.

7. An oil well derrick comprising a substructure, a mast having an upper section and an open front lower section detachably connected together, a track extending lengthwise of the outside of the back of said upper section, bearing members carried by the upper end of said lower section, said sections being of such shape that the upper section is capable of being telescoped into the lower section when they are disconnected from each other, a sheave mounted in the lower end of said upper section, means for pivotally connecting the lower end of the mast to the substructure so that the mast can be swung forward and down from an upright position to a prone position thus permitting its upper section to rest on a vehicle, and means connecting a line extending over said sheave to a point on said prone lower section below the sheave for lifting the upper end of the prone lower section after it has been disconnected from the prone upper section and seating said bearing members on the track, whereby movement of the vehicle toward the substructure will telescope the upper section of the mast into its lower section, after which the lower end of the mast can be disconnected from the substructure to permit the nested mast sections to be carried away by the vehicle.

8. In an oil well derrick, a substructure including a normally horizontal arm means pivoted at its front end on a horizontal axis to the top of the rest of the substructure, a mast having front and rear legs, and means pivotally connecting the lower ends of the rear legs of the mast to the rear end of said arm means so that the mast can be swung forward and down from an upright position to a prone position on a vehicle, said arm means being adapted to swing

upward to permit said prone mast to lie flat on the vehicle.
